UNITED STATES PATENT OFFICE.

LYMAN G. KEYES, OF NATIONAL MILITARY HOME, KANSAS.

LOCKING-BOLT-OPERATING DEVICE.

1,270,740.

Specification of Letters Patent. Patented June 25, 1918.

Application filed April 17, 1918. Serial No. 229,092.

To all whom it may concern:

Be it known that I, LYMAN G. KEYES, a citizen of the United States, and a resident of National Military Home, in the county of 5 Leavenworth and State of Kansas, have invented a new and Improved Locking-Bolt-Operating Device, of which the following is a full, clear, and exact description.

This invention relates to locking bolts of 10 that type especially adapted for but not necessarily limited to double doors, double hinged window sashes and the like, and the invention has to deal more particularly with an operating means which automatically locks the bolt or bolts in either extreme position, so that it is impossible to move the bolt or bolts except by the direct action of 15 the operating means, as, for instance, by the turning of the handle of the device.

The invention has for its general objects 20 to provide an improved operating means for the head and foot bolts of the locking device so as to be reliable and efficient in use, comparatively simple and inexpensive to 25 construct, of durable and substantial design, and capable of automatically locking the bolts when fully projected or retracted, and keeping them locked at all times, except when the handle or lever of the operating

means is actuated. 30 A more specific object of the invention is the provision of a detent or catch within the operating device and so related to the handle that the detent becomes automatically released at the beginning of the movement of the handle and automatically set at the end of the movement, there being a slight lost motion between the handle and the locking bolts to provide for the initial

40 releasing of the detent or catch and the final setting thereof during each full swing of the handle.

For a more complete understanding of the invention reference is to be had to the following description and claims taken in connection with the accompanying drawings, wherein similar characters of reference indicate corresponding parts in all the views, in which—

50 Figure 1 is a front view of a double door with the locking means applied thereto;

Fig. 2 is an enlarged front view of the bolt-operating means of the device;

Fig. 3 is an enlarged view on the line 3—3, Fig. 2;

Fig. 4 is a vertical section on the line 4—4, Fig. 3;

Fig. 5 is a section on the line 5—5, Fig. 3, with the operating handle in mid position;

Fig. 6 is a similar view with the handle 60 in one of its extreme positions;

Fig. 7 is a perspective view of the bolt-actuating plate; and

Fig. 8 is a detail view showing the action 65 of the locking detent.

Referring to the drawing, A and A' designate double doors, the latter door being normally locked by head and foot bolts 1 and 2 actuated by an operating device B and movable in guides 3 to engage keepers 4 at 70 the top and bottom of the door frame.

The operating device B comprises a frame or base section 5 in the form of a plate which is rigidly secured to the door A' by screws or equivalent fastenings 6 and which has a 75 circular flange 7. In front of the base or back section 5 is a rotatable plate 8 which turns on a central stud or pivot 9 screwed into a central boss 10 on the back section 5, and on this front section or plate 8 are fixed 80 pins 11 which extend into the chamber 12 and engage in elongated openings 13 in the offset ends 14 of the locking bolts 1 and 2, which latter enter the casing of the locking device through openings 15 in the circumferential flange 7.

On the stud 9 swings an operating handle 16 which has a lost motion connection with the plate or disk 8, by reason of a pair of screws 17 and 18, which screw into the under side of the handle and are engaged respectively in slots 17^a and 18^a in the disk 8.

The head of the screw 17 is countersunk in the disk 8 and the slot 18^a for the screw 18 is located in an extension 19 in one edge of 95 the plate or disk 8. On the under side of this extension are spaced lugs 20 which are adapted to engage the bosses 21 on the base section to limit the swinging movement of the handle 16, as clearly shown in Fig. 6. 100

The lost motion between the handle and the bolt-throwing plate 8 is utilized for the

throwing into and out of operation of a locking means for preventing the bolt from being operated from either extreme position, except by the throwing of the handle 16. 5 This locking means comprises an oscillatory 10 detent 22 which has a central fulcrum 23 rocking on a bearing 24 on the plate 8, and the oppositely-extending arms 25 of the 15 detent have bevel lugs 26 which coöperate with the ends 27 of an arcuate track 28 formed 20 on the internal surface of the circumferential flange 7 of the casing or base section 5. At the center of the detent is a lug 29 which engages in a recess 30 in the wall of 15 the chamber 31 in the handle 16, so that when the handle is moved in one direction or the other the detent is oscillated around the fulcrum 23 as a center when the handle is in either extreme position. At any intermediate 20 position of the handle the lugs 26 of the detent ride on the track 28, and as soon as the forward lug of the detent reaches the end of the track the detent is oscillated by the continued movement of the handle 25 until the latter is stopped by a lug 20 engaging a boss 21. At the beginning of the movement of the handle from the extreme position, the detent is oscillated from an inclined position so as to disengage the end 30 of the track 18, which permits the handle to be operated to throw the bolts in one direction or the other. In Fig. 8 the detent is shown in full lines in position for locking the bolts, and as soon as the handle is moved, 35 the detent is tilted and the handle then moves while the detent is in the position shown by the dotted lines *a*, and when the handle reaches the end of the movement the detent is automatically tilted to the position 40 shown at *b*, which is inclined oppositely from the initial position of the detent, thus again locking the bolts.

Within the chamber 31 is a bowed spring 32 which is anchored at 33 and has its central portion resting on a projection 34 carried by the detent so that the detent is always under spring pressure acting to hold the detent in either extreme position or a central position.

60 From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown 65 is merely illustrative and that such changes may be made when desired as fall within the scope of the appended claims.

Having thus described my invention, I

claim as new and desire to secure by Letters Patent:

65

1. A device of the class described comprising a casing having an arcuate track, a plate pivoted on the casing, a bolt extending into the casing, a connection between the plate and bolt, said plate being open at a point adjacent the track, a detent mounted outside the plate and having members extending through the plate to engage with the track, a handle pivoted outside the plate and having a lost motion connection therewith, and interengaging means between the handle and detent for oscillating the latter at the end of the movement of the handle in either direction for engaging the lugs of the detent with the ends of the track, said lugs being slidable on the track during the movement of the handle with the plate. 75

2. A device of the class described comprising a bolt, a bolt-throwing member, a supporting element, a stud on the element and on which the member turns, a handle connected with the stud to turn around the same as a center, a lost motion connection between the member and handle, said handle having a chamber, a detent fulcrumed on the member and disposed in the chamber of the handle, interengaging means between the detent and handle, whereby the movement of the latter tilts the detent, and spaced means on the said element with which the detent automatically engages at the end of the movement of the handle in either direction for preventing movement of the bolt except by the movement of the handle. 95

3. A device of the class described comprising a bolt, a bolt-throwing member, a supporting element, a stud on the element and on which the member turns, a handle connected with the stud to turn around the same as a center, a lost motion connection 100 between the member and handle, said handle having a chamber, a detent fulcrumed on the member and disposed in the chamber of the handle, interengaging means between the detent and handle, whereby the movement of the latter tilts the detent, spaced means on the said element with which the detent automatically engages at the end of the movement of the handle in either direction for preventing movement of the bolt except by the movement of the handle. 105

4. A device of the class described comprising a bolt, a bolt-throwing member, a supporting element, a stud on the element and on which the member turns, a handle connected with the stud to turn around the same as a center, a lost motion connection 110 between the member and handle, said handle having a chamber, a detent fulcrumed on the member and disposed in the chamber of the handle, interengaging means between the detent and handle, whereby the movement of the latter tilts the detent, spaced means on the said element with which the detent automatically engages at the end of the movement of the handle in either direction for preventing movement of the bolt except by the movement of the handle, and a spring disposed in the chamber of the handle and engaging the detent for yieldingly holding the same in its locking position. 115

4. A device of the class described comprising a bolt, a bolt-throwing member, a supporting element, a stud on the element and on which the member turns, a handle connected with the stud to turn around the same as a center, a lost motion connection 120 between the member and handle, said han-

125

dle having a chamber, a detent fulcrumed on the plate and disposed in the chamber of the handle, interengaging means between the detent and handle, whereby the movement of the latter tilts the detent, spaced means on the said element with which the detent automatically engages at the end of

the movement of the handle in either direction for preventing movement of the bolt except by the movement of the handle, and 10 stops for limiting the movement of the handle.

LYMAN G. KEYES.
